[57] **CLAIM**

The ornamental design for a plastic bag holder, as shown and described.

DESCRIPTION

FIG. 1 is a top, front, and right side perspective view of a plastic bag holder showing my new design;

FIG. 2 is an enlarged right side elevational view thereof, the left side being a mirror image of that shown;

FIG. 3 is an enlarged front elevational view thereof;

FIG. 4 is an enlarged top plan view thereof;

FIG. 5 is an enlarged bottom plan view thereof; and,

FIG. 6 is an enlarged rear elevational view thereof.

The plastic bag and a cabinet drawer shown in broken lines in FIG. 1 denote the nature and environmental use of the design and are not part of the design.
